UNITED STATES PATENT OFFICE.

GEORGE F. RENDALL, OF NEW YORK, N. Y., ASSIGNOR TO CARBON PRODUCTS COMPANY, A CORPORATION OF DELAWARE.

DISTILLATION-RETORT AND SEPARATING-TANK.

1,345,404.

Specification of Letters Patent.

Patented July 6, 1920.

Application filed June 13, 1917, Serial No. 174,437. Renewed May 26, 1920. Serial No. 384,508.

To all whom it may concern:

Be it known that I, GEORGE F. RENDALL, a citizen of the United States, residing in the city and county of New York, State of New York, have invented a new and useful 5 Distillation - Retort and Separating - Tanks, of which the following is a specification.

My invention relates to an apparatus for the treatment of solid material or any material that becomes volatile under heat and further enables said volatile material to be 10 extracted from the retort in which it is treated and be precipitated in a plurality of tanks according to the specific gravity 15 of the material volatilized.

A further object of my invention is to provide an apparatus which enables the treated material and the volatile products to be extracted without loss and without 20 the creation of any fumes.

Another object of my invention is to provide an apparatus, which permits the expulsion of all air from the retort in the treatment of the materials contained therein to prevent oxidizing, and I also provide 25 means for cooling the material in the retort after distillation thereof, so that the product can be extracted from the retort without endangering loss by combustion.

A still further object of my invention is to provide an apparatus of this character, wherein a novel construction of burner is employed to produce an efficient combustion in relation to the retort containing the material to be distilled.

For the purpose of illustrating my invention, I have shown in the accompanying drawings one form thereof which is at present preferred by me, since the same 40 will give in practice satisfactory and reliable results, although it is to be understood that the various instrumentalities of which my invention consists can be variously arranged and organized and that my 45 invention is not limited to the precise arrangement and organization of these instrumentalities as herein shown and described.

Figure 1 represents a side elevation, partly in section, of a distillation apparatus 50 embodying my invention.

Fig. 2 represents a vertical transverse section, partly in elevation, through the furnace showing another embodiment of my invention.

Fig. 3 represents a view similar to Fig. 2,

showing a still further embodiment of my invention.

Similar numerals of reference indicate corresponding parts in the figures.

Referring to the drawings:—

Referring to the embodiment of my invention in Fig. 1, 1 designates a furnace having a combustion chamber 2, in which is located the retort 3 supported in the front and rear walls 4 and 5 of the furnace. 6 and 7 designate angular members or brackets secured to the front and rear walls 4 and 5 of the furnace for effectively supporting said retort, which is preferably composed of a refractory material, such as 65 fire clay capable of standing high heat and internal pressure without cracking and enabling the material to be internally cooled without cracking the outer shell.

8 designates a manhole for the reception 75 of carbonaceous material, such as bituminous coal into the retort, wherein the material is subject to distillation. 9 and 10 designate manholes for the extraction of solid products and 11 designates an outlet 80 for drawing off the liquids from the retort, such as tar, creosote and carbolic acid, etc., after distillation of the carbonaceous materials.

These manholes are provided with steam 85 tight closures 12, 13 and 14, so as to hermetically seal the interior and subject the material contained in the retort to the action of the steam employed for purposes of distillation.

Combustion in the combustion chamber 2 is preferably produced by gas of the producer type fed into a plurality of burners 15 through the inlet pipe 16 controlled by the valve 17. The burners 15 consist of 95 longitudinal tubes 18 perforated, as at 19, for the discharge of gas for combustion purposes. 20 designates regulator caps for closing the ends of the burners. These regulator caps have openings adjustably arranged in relation to openings in the burner tubes for the admission of preheated air into the burners to mix with the gas. Intermediate of these regulator caps 20, T's 21 are arranged which are provided with 100 downwardly threaded extensions 22 screwing into the blocks 23 secured to the perforated partition 24. In this manner, the burners 15 may be adjusted vertically in relation to the bottom of the retort accord- 110

ing to the class of material to be distilled and the various methods of distillation employed.

5 A pilot light 25 supplied with gas from without is located in the combustion chamber adjacent the burners for lighting the burners 15. Access to the combustion chamber 2 and to the burners 15 located therein is had through the fire door 26 in front wall 14 of the furnace 1.

1 A 27 designates a chimney for the discharge of used gases from the furnace.

15 Below the partition 24, an air chamber 27 is located for preheating air prior to its discharge through the perforations 28 of the partition 24 into the combustion chamber 2 to support combustion of the gases. 29 designates an air inlet pipe through which air is fed into the air chamber 27, the flow of air through this pipe into the air chamber 27 being controlled by the valve 30.

25 31 designates a steam supply pipe provided with the valve 32 for the control of a continuous or intermittent injection of steam, preferably in a superheated condition into the retort 3.

30 The steam in a highly superheated condition passes through the retort 3 carrying therewith the volatile gases of distillation into a pipe 33 provided with the depending tap pipes 34, 35 and 36 communicating with a plurality of condensation tanks 37, 38 and 39 water jacketed as shown at 40 and provided with suitable means for determining the quantity of material contained therein. 41, 42 and 43 designate outlet valves for drawing off the contents contained in the condensation tanks 37, 38 40 and 39.

45 The pipe 33 is plugged at 44 and provided with the valves 45, 46 and 47 for directing the volatile gases into the desired condensation tanks according to the specific gravity thereof.

50 48 designates a pipe provided with the valve 49 for conducting wet steam into the pipe 31, which flows thence into the retort 3 for application to the solids after distillation preparatory to the removal of said solids from said retort.

55 In Fig. 2, another embodiment of my invention is shown, wherein is represented a vertical transverse sectional view, partly in elevation, of the furnace 50 of which 51 is the combustion chamber. 52 designates a retort located in the combustion chamber 51. This retort is provided with the longitudinal tongues 53 embedded in and supported 60 by the side walls 55 and 56. 57 designates a manhole for the reception of the carbonaceous material into the retort, said manhole being provided with the steam tight cover 58.

65 59 designates a manhole for the removal

of the solid products after the distillation thereof.

60 designates the inlet pipe for the injection of a continuous or intermittent stream of superheated steam into the retort. 70

Combustion in the combustion chamber 51 is preferably produced by burners 61, which consists of a plurality of perforated transverse tubes 62 of a curvature conforming with the contour of the retort 52. The ends 75 of the tubes 62 are closed by the regulator caps 63, while intermediate these caps, T's 64 are arranged, the burner tubes 62 and the threaded extensions 65 being adapted to be screwed into the blocks 66 secured to the 80 perforated partition 67, for the vertical adjustment of the burners in relation to the retort. Gas is supplied to the burners 61 by the inlet pipe 77 provided with the valve 78 for controlling the supply of gas. A 85 pilot light 68 is located in the combustion chamber adjacent the burners for lighting the burners.

69 designates a chimney for the discharge of used gases from the combustion chamber. 90 Air for supporting combustion of the gases is supplied to the combustion chamber from the air chamber 70 through the perforations 71 in the partition 67. 72 designates an inlet pipe for the supply of air into the 95 air chamber 70.

In Fig. 3, a still further embodiment of my invention is shown, in which is represented a view similar to that of Fig. 2, wherein a different method is used for producing combustion by gas, which consists in arranging several layers of spherical objects 73 on the perforated partition 67. These spheres 73 are preferably composed of fire clay or other refractory material to 105 prevent burning out and allow for the ready removal and replacing of the same.

The gas chamber 74 below the perforated partition 67 is provided with the inlets 75 and 76 for the supply of gas and air. With 110 an arrangement of this character it can readily be seen that an even fire surface is produced in the combustion chamber. It will be of course understood that the spheres 73 can be arranged in any suitable manner to 115 produce the best combustion results in relation to the retort 52.

In the operation of my novel apparatus, the carbonaceous materials are placed in the retort through the manhole 8, this manhole 120 is then closed by the steam tight cover 12, the valve 32 is then operated intermittently to inject superheated steam into the retort to remove the air therefrom, and after the air is removed, the superheated steam is 125 turned into the retort in a continuous stream. Combustion is then produced by the burners 18 controlled by the valve 17 and lighted by the pilot light 25.

With combustion in the combustion cham- 130

ber 2, the volatile gases will be separated from the solids in the retort 32 and from an admixture with the superheated steam. The admixture of superheated steam and 5 volatile gases is then carried by the continuous flow of steam into the distributing pipe 33 where the gases, according to their specific gravity, are precipitated into the respective condensation tanks 37, 38 and 39.

10 The remaining solids produced in the retort are then subjected to wet steam from the pipe 48 to allow for the ready removal of the same through the manholes 9 and 10 and the outlet 11.

15 The burners 18, 61 may be readily adjusted and arranged in relation to their respective retorts to produce the most efficient combustion.

It will now be apparent that I have devised a novel and useful distillation retort and separating tanks, which embodies the features of advantage enumerated as desirable in the statement of the invention and the above description, and while I have, in 25 the present instance, shown and described a preferred embodiment thereof which will give in practice satisfactory and reliable results, it is to be understood that the same is susceptible of modification in various particulars without departing from the spirit or 30 scope of the invention or sacrificing any of its advantages.

Having thus described my invention, what I claim as new and desire to secure by Letters Patent, is:—

35

1. An apparatus of the character described, comprising a combustion chamber, a material containing retort therein, an air chamber, a perforated partition separating said combustion chamber from said air 40 chamber, burners adjustably supported on said partition in said combustion chamber, regulator caps on said burners for the admission of preheated air into said burners, and a gas supply pipe communicating with said 45 burners from without the combustion chamber.

2. An apparatus of the character described, comprising a combustion chamber, a material containing retort therein, an air 50 chamber, a perforated partition separating said combustion chamber from said air chamber, burners adjustably supported on said partition in said combustion chamber, regulator caps on said burners for the ad- 55 mission of preheated air into said burners, a gas supply pipe communicating with said burners from without the combustion chamber, and means for controlling the supply of gas into said burners.

GEORGE F. RENDALL.
